UNITED STATES PATENT OFFICE.

CHARLES P. TOLMAN, OF NEW ROCHELLE, NEW YORK, ASSIGNOR TO NATIONAL LEAD COMPANY, OF NEW YORK, N. Y., A CORPORATION OF NEW JERSEY.

CENTRIFUGAL SEPARATOR.

1,358,897.

Specification of Letters Patent. Patented Nov. 16, 1920.

Application filed April 2, 1917. Serial No. 159,085.

To all whom it may concern:

Be it known that I, CHARLES P. TOLMAN, a United States citizen, residing in New Rochelle, New York, have invented the following described Improvements in Centrifugal Separators.

The invention consists in the structure and mode of operation of apparatus operating through the effect of centrifugal action to 10 separate the heavier and lighter components of fluid mixtures, such for example as the white lead and the water in the material commercially known as lead pulp and also for separating slimes and other similar mixtures of materials of different specific gravities. The object of the invention is to 15 produce apparatus of the character indicated capable of separating a continuous supply of the material stated, automatically 20 and with substantial uniformity as respects the thoroughness of the separation, and under control while in action, and which is specially adapted for operation on material 25 which is sticky when moist as in the case of lead pulp. The invention however also includes details and incidental features which are capable of use in improvement upon previously known centrifugal separators and 30 these are herein independently claimed in such broader relation.

In the accompanying drawings:

Figure 1 is a vertical section of a preferred embodiment of the invention;

Fig. 2 a horizontal section on line II—II;

35 and

Fig. 3 a section on line III—III.

The machine comprises a separating chamber formed of relatively separable chamber sections shown in the present case as a lower 40 section 1 and an upper or cover section 2, providing within and between them an interior separating space into which the material to be separated is introduced and in which the heavier or solid materials, by flowing 45 toward the region of widest diameter under the centrifugal effect crowds the sections apart and thereby forces an escape through the annular peripheral outlet thus opened, while the lighter material not subject to the same degree of centrifugal pressure 50 flows out through one or more exits disposed inward of the peripheral outlet. A yielding force or spring tends to close the outlet between the sections to produce an initial centrifugal accumulation of the

heavier material adjacent the junction between the sections, and may be adjusted in reference to the angular rate of rotation of the chamber, the diameter thereof, and the character of the material treated, so as to 60 maintain a rate of peripheral discharge substantially constant and therefore readily equalized to the rate of interior accumulation of the solid, without passing any considerable part of the lighter material along 65 with the heavier.

The rotary motion is imparted to the material through the lower section 1 which is bowl shaped with sloping side walls, the slope of which is more or less steep according to the material treated. The said section is carried by an upright rotary shaft 3, journaled in a substantial framework 4 and driven by a belt gearing 3^a from a drive shaft 5 at one side of the framework. 75

The material is supplied to the bowl chamber through the shaft 3 which is hollow for that purpose, and enters the shaft preferably at its upper end and through a stationary inlet connection head 6 with 80 which the upper part of the shaft makes a leak-tight connection as indicated in the drawing. The conduit through the shaft opens in one or more holes 7 which are located at the narrow or bottom part of the 85 chamber section 1, so that the constituent materials may have an opportunity to separate, undisturbed from the incoming liquid, while rising in the bowl chamber toward the outlets, both of which are near 90 the top of the chamber.

The upper chamber section 2 is constituted, in the present case, of an essentially flat or disk form cover member adapted to fit tightly on the flanged margin 8 of the 95 lower section and provided with a sleeved bearing 9 on which it may slide on the vertical shaft 3 to open the peripheral outlet. This cover member is urged in the direction to close such outlet by its gravity in the present case, and also by the pressure of a thrust sleeve 10 contained within its upstanding tubular boss and thrusting thereon through a bearing which permits the rotation of the chamber section. A ball thrust bearing is 100 used for this purpose and is contained within the cover section 2 where it is least likely to accumulate dirt. The thrust sleeve extends above the boss where it carries, on its flanged head, a ring 11 the trunnions 12 of 105 110

which are engaged by a lever structure 13 fulcrumed on the frame at 14 and extending to one side of the frame where it is connected to one end of the spring 15, the other 5 end of which is connected to the frame by the spring adjustment devices 16. The spring 15, which may be assumed to represent any suitable and controllable force, exerts its pressure through the lever and thrust 10 sleeve upon the cover member 1 tending to close it against the centrifugal pressure of the chamber contents acting on the under side of it, and by virtue of the rotary bearing the said closing pressure so exerted, can 15 be varied while the cover section is in rotation.

The cover section 2 is rotated in the present case, independently of the bowl section, and by means of a belt and belt pulley 20 17 which latter constitutes the upper part of or a continuation of the tubular boss of the cover member. The belt drive for the cover section allows it to slide upon the shaft 3 quite the same as if the cover section were 25 splined to it, but the independent drive affords the advantage of a differential rotary motion between the chamber sections which is desirable in the case of the materials herefore indicated and which serves to pre- 30 serve uniform conditions of outflow at all points around the peripheral outlet between the sections. The pulley diameters in the drawings will be seen to give a higher rotation to the cover than the bowl section 35 but of course the differential rotation of one section with respect to the other or to the contents of the chamber may be obtained in other ways and with the same effect. The outflow from between the chamber sections 40 is retarded, relatively speaking, by the extent of the frictional surface constituting the escape orifice of the outlet and it is desirable to extend such surfaces radially in order to increase the frictional resistance to 45 outflow, by forming the flange 8 on the rim of the lower section. The upper surface of this flanged rim, and the corresponding surface on the movable cover may be of greater radial dimension, than indicated in the drawings and as wide as found best for the 50 particular material in treatment.

The centrifugally discharged heavier material, escaping through the annular outlet between chamber sections is caught in an 55 annular receptacle 18 surrounding the flange 8 and opening inward or toward the axis of the chamber and this receptacle is mounted on rollers 19 or otherwise supported so that it may be rotated around the 60 separating chamber by means of its gear teeth 20 and a slow pinion 21, the latter being understood to be appropriately driven from the power shaft 5 by a gearing not necessary to be shown. The frame bracket 65 22 carries a fixed scraper 23 engaging the

traveling collector trough 18 at a fixed point and evacuating its contents into a delivery chute or other suitable conveyer 24.

The outlet for the separated lighter components of the treated mixture is at the top 70 of the separating chamber near the hub part 9 and represented by a series of open holes 25 in the cover. The lighter material flows upwardly through these holes into and across the basin 26 formed in the upper surface of the cover section and off the lip 27 of said basin into the annular collecting chamber 28 which is or may be stationary and surrounds the cover section immediately above the receptacle 18 for the heavy ma- 75 terial. This receptacle is provided with an off-take 29. In the case of the illustrated machine it is assumed that the upper chamber section is to be rotated at a sufficient velocity to discharge the lighter liquid across 80 the gap between the lip 27 and the trough or collecting receptacle 28, and the margin of the said section is curved or shaped in a suitable way to minimize leakage at this point and under all positions of separation 90 of the chamber sections.

The operation of the apparatus will be understood to be subject to variation according to the material treated and to be supplemented by such additional appurtenances 95 as may be necessary to impart a proper rotary velocity to the said material irrespective of whether one or both chamber sections rotate with it or at the same velocity, it being preferable that the rotary velocity of 100 the material at the peripheral outlet be constant so that the regulation of discharge of the heavier material may be effected solely through the adjustment of the closing pressure. It will be apparent that the 105 only force tending to open the peripheral outlet is the interior centrifugal pressure of the chamber contents and that, within the capacity of the apparatus, such opening can be resisted to various extents by the adjustment of the spring so as thereby to control the degree of separation of the lighter 110 from the heavier components, and that such adjustment when properly coördinated with the control of inflow through the inlet head 115 6 will permit continuous separation of a continuous supply. The invention is not limited to the differential rotation of the chamber sections because equal velocities may be used effectively on some materials, 120 nor is it confined to any particular shape of the separating chamber although the relatively deep chamber giving an opportunity for a well established upward flow therein during separation is most satisfactory and 125 most effective. The depth of the chamber allows a time interval for separation which may be increased by increasing the depth of the chamber relatively to its diameter while maintaining the general flow from one end 130

to the other in the direction of the axis of rotation. It will be recognized as a matter of much practical advantage that the peripheral outlet is continuous around the 5 chamber and unobstructed inasmuch as thereby the accumulation of the heavier material is kept uniform at all points around the periphery and the machine thereby remains in balance. And that the relative motion 10 of the edges or lips of the orifice, both as regards proximity of contact under the influence of the force exerted by the accumulation of the heavier material and the relative rotation in the structure shown due 15 to the differential drive of the two parts of the chamber, is of material importance to prevent clogging of the orifice.

It should be stated in conclusion that the drawings hereto are mainly illustrative of 20 the best mode in which I have contemplated applying the principles of my invention at the present time, and that the invention is not limited in respect to the size, proportion, structure or relative arrangement of 25 the parts and various reversals, modification, additions to and subtractions from the said structure may be made within the scope of the following claims.

I claim:

1. A centrifugal separator comprising a separating chamber formed of sections adapted to separate under centrifugal action against a force tending to close them together and by their separation to open a peripheral annular outlet between them for the escape of heavier material, and further provided with an outlet for lighter material inward of said peripheral outlet, in combination with means for continuously 40 supplying the material to be separated to the chamber, and means whereby the relatively separable chamber sections are rotated at different speeds.

2. A centrifugal separator comprising a separating chamber formed of a bowl section and a cover section, the cover section being automatically movable away from the bowl section to open a peripheral annular outlet at the top of the separating chamber 50 and having another outlet toward the center, and means whereby the bowl and cover sections are rotated at different speeds.

3. A centrifugal separator comprising a separating chamber formed of a bowl section and a disk-like cover section between which the heavier material escapes through a peripheral annular outlet, said cover section having one or more openings in its inner portion for escape of lighter material, 60 and means for rotating said sections at different speeds.

4. In a centrifugal separator, the combination of chamber sections, an axial support whereon said sections are mounted and

are relatively separable under centrifugal 65 action to open a continuous unobstructed peripheral outlet between them for the escape of heavier material, the upper section having an outlet for lighter material inward of said peripheral outlet, coaxial means for 70 pressing the chamber sections together, and means for rotating the sections at different speeds.

5. In a centrifugal separator, the combination of a central shaft, rotatable bowl and 75 cover sections thereon, the cover section being vertically movable on the shaft to open a peripheral outlet for heavier material and having an outlet toward the center for lighter material, and means including a 80 thrust sleeve encircling the shaft and bearing upon the cover section for imparting a yielding pressure thereto.

6. A centrifugal separator comprising a 85 bowl section and a cover section between which the heavier material escapes through a peripheral annular outlet, said cover section having a central upstanding tubular boss and one or more escape openings for lighter material between said boss and the 90 peripheral outlet, and means for applying yielding pressure to said tubular boss.

7. A centrifugal separator comprising a separating chamber formed of chamber sections relatively separable against a force 95 tending to close them together and adapted by their separation to open a peripheral annular outlet between them for escape of heavier material and provided with an outlet for lighter material inward of said peripheral outlet, in combination with a conduit supplying the material to be separated to said chamber, means for imparting adequate rotary motion to said material to cause it to open said peripheral outlet, a rotary 100 collecting receptacle for said outlet and a stationary scraper coöperating with said receptacle to deliver the accumulation thereon.

8. A centrifugal separator comprising a 110 rotary separating chamber having a peripheral outlet for heavy material and an outlet inward thereof for light material, in combination with a rotary receptacle concentrically surrounding said chamber to collect the heavy material and means for evacuating 115 said receptacle.

9. A centrifugal separator comprising a separating chamber of relatively separable chamber sections between which the heavier material escapes through a peripheral annular outlet, one of said sections having one or more openings for escape of lighter material, and means for rotating one of said sections relatively to the other. 120

In testimony whereof, I have signed this 125 specification.

CHARLES P. TOLMAN.
